Des. 173,860
Patented Jan. 11, 1955

173,860

ORNAMENTAL CROSS

Calvin A. Seisholtz, Jr., Allentown, Pa.

Application August 26, 1953, Serial No. 26,593

Term of patent 7 years

(Cl. D29—23)

FIG. 1

Des. 173,860

PAGE 2

To all whom it may concern:

Be it known that I, Calvin A. Seisholtz, Jr., a citizen of the United States of America, residing at Allentown, in the county of Lehigh and State of Pennsylvania, have invented a new, original, and ornamental Design for an Ornamental Cross, of which the following is a specification, reference being had to the accompanying drawing, forming a part thereof, wherein:

Fig. 1 is a front elevational view of an ornamental cross, showing my new design;

Fig. 2 is a side elevational view thereof; and

Fig. 3 is a top plan view thereof.

I claim:

The ornamental design for an ornamental cross, as shown.
